COP HOLDING DEVICE FOR LOOM
SHUTTLESWaldo L. Davis, Hopedale, and Daniel M. Chase,
Wilkinsonville, Mass.

Application October 24, 1932, Serial No. 639,254

1 Claim. (Cl. 139—210)

This invention relates to loom shuttles provided with spindles on which cops or tubes of paper or similar material may be placed. In modern high speed looms, the repeated abrupt 5 checking of the shuttle has a strong tendency to loosen the cop on the spindle, causing weft breakage and stoppage of the loom.

It is the general object of our invention to provide means by which the cops may be more 10 effectively held on the spindles, while at the same time they are readily removable therefrom without injury to the cops.

A more specific object is to provide an expanding type of cop spindle with a pad or portion of 15 rubber or similar frictional cushion material, which material will be brought into holding engagement with the cop by the expanding action of the spindle and which material will be withdrawn from such engagement on contraction of 20 the spindle.

Our invention further relates to arrangements and combinations of parts which will be herein-after described and more particularly pointed out in the appended claim.

25 A preferred form of our invention, together with certain modifications, is shown in the drawing, in which

Fig. 1 is a partial sectional side elevation of a shuttle embodying our improvements;

30 Fig. 2 is a view similar to Fig. 1 but showing the parts in a different position;

Fig. 3 is a partial plan view of the spindle, looking in the direction of the arrow 3 in Fig. 2;

Figs. 4, 5 and 6 are side elevations of spindles 35 embodying modified forms of our invention, and

Fig. 7 is a detail plan view, looking in the direction of the arrow 7 in Fig. 6.

Referring to Figs. 1 to 3, we have shown a 40 shuttle S having a spindle 10 of the expanding type and provided with a main part 11 and a resilient movable portion or feather 12. The spindle 10 is pivoted on a cross stud 14 fixed in the body of the spindle and is mounted to swing in a vertical recess 15 in the shuttle body.

45 A flat spring 17 acts on the upper part of the spindle butt and holds the spindle yieldingly in the open position shown in Fig. 2 or the closed and operative position shown in Fig. 1. When the spindle is swung upward to open position, as shown in Fig. 2, the end of the spring 17 engages a beveled portion 18 on the end of the feather 12 and forces the feather toward the main part 11 of the spindle, thus contracting the spindle.

50 As the spindle is swung downward to operative

position, the feather 12 is released and springs upward, thus in effect expanding the spindle within the cop C. A cross pin 20 (Figs. 1 and 2) is engaged by a depending portion 21 on the spindle 10 and acts as a stop for definitely positioning the spindle in horizontal or operative position. 5

In the preferred form of our invention, the expanding portion or feather 12 of the spindle 10 is recessed as indicated at 24 in Fig. 3 to receive 10 a sleeve or tube 25 of resilient cushion material such as soft rubber. This cushion material preferably extends slightly beyond the normal engaging surface of the feather 12 but does not extend sufficiently to interfere with application of a cop 15 when the spindle 10 is raised and contracted.

When the spindle is thereafter swung downward to operative position, however, the rubber sleeve or tube 25 is pressed outward against the inside of the cop in a firm frictional engagement 20 which securely holds the cop from axial displacement on the spindle. When the cop is to be removed, the spindle is swung upward and is thereby contracted, thus relieving the frictional engagement so that the cop is free for convenient 25 removal.

While we have shown the rubber surface as forming a portion of a sleeve or tube in our preferred form, the manner of application of the rubber to the spindle feather may be varied, as 30 shown for instance in Figs. 6 and 7, in which a rubber thread 30 is laced into a series of holes 31 in the spindle feather 32. With this construction, the rubber is even more securely held in place 35 than in the form previously described.

In Fig. 4 we have shown a rubber tube or sleeve 35 mounted in a recess 36 near the base of the main spindle portion 37. When the feather is released, the spindle expands as usual and the cop C is forced against the sleeve 35, the operation 40 being substantially as previously described.

The method of application of the rubber tube to the spindle is somewhat more simple, however, in the construction shown in Figs. 1 to 3, as in that construction the tube may be easily 45 slipped over the free end of the feather.

In the construction shown in Fig. 5, we have provided recesses 40 and 41 in both portions of the spindle and have provided a rubber sleeve or tube 42 which encircles both spindle portions. 50 In this case, as the spindle expands the rubber sleeve 42 is stretched until it firmly engages the cop C.

55 In each form of the invention, it will be seen that a frictional surface of rubber or other suit-

able cushion material is provided, which surface is withdrawn during the application or removal of the cop but is moved outward by the expansion of the spindle to firmly engage the cop as 5 the spindle is moved to operative position.

The invention has been found extremely satisfactory in use and effectively prevents axial displacement of cops in modern high speed looms. Furthermore, the inside of the cop is not injured by its application to or removal from the 10 spindle, and the cops may be used repeatedly, thus reducing the expense of loom operation.

Having thus described our invention and the advantages thereof, we do not wish to be limited

to the details herein disclosed, otherwise than as set forth in the claim, but what we claim is:—

In a loom shuttle, an expanding two-part cop-holding spindle, means to cause expansion and contraction of said spindle, and a portion of rubber tube having a soft compressible surface encircling one only of the two relatively movable parts of said spindle so that the spindle backs it up and positioned thereon to engage the inner surface of a paper cop as said spindle expands, 10 said spindle part being recessed to provide a depressed seat for said rubber tube portion.
